UNITED STATES PATENT OFFICE

2,482,673

DRAINAGE SYSTEM

Walter Kjellman, Stockholm, Sweden

Application January 22, 1948, Serial No. 3,710
In Sweden December 12, 1945Section 1, Public Law 690, August 2, 1946
Patent expires December 12, 1965

10 Claims. (Cl. 61—11)

1

This application is a continuation in part replacing my copending application Serial No. 636,416, filed December 21, 1945 now abandoned, and, as to all common subject matter, relates back to said application Serial No. 636,416, and to foreign applications corresponding thereto for all dates and rights incident to the filing thereof.

The present invention relates to a drainage system. In my copending application Serial No. 762,946, I have suggested to reduce the percentage of water in clay grounds and similar grounds by the arrangement of vertical band-shaped drains in the ground, said drains being made from a material pervious to water. The drains facilitate the escape of such pore water as is being squeezed out of the ground by the load that is applied on the ground surface. Thus, the consolidation of the ground is accelerated, the purpose being to increase the carrying capacity of the ground and/or to accelerate settlements. There is a twofold purpose of the band or strip-shape of the drain, firstly to reduce the amount of drain material in relation to the area of contact between drain and soil, the draining effect being dependent mainly on the size of said area, and, secondly, to render the drain flexible so that it can be rolled on a drum and easily transported and handled.

The material of said drains must be very porous, and the pores must be large, in order that the permeability of the drain to water shall be sufficient in the longitudinal direction thereof. Furthermore, the material must be capable of withstanding the horizontal earth pressure without loosing too much in permeability. Finally, even very small soil grains must be prevented from entering the pores of the material, because they could clog there, thus reducing the permeability of the drain. In certain cases it has been found difficult to answer all of these requirements.

It is the object of the present invention to provide band-shaped draining means which are capable of withstanding the earth pressure and into which soil grains cannot penetrate, while the draining means yet have sufficient permeability.

In the drawings:

Fig. 1 is a horizontal sectional view substantially at right angles to the longitudinal direction of a drain and showing one form of the invention.

Fig. 2 is a horizontal sectional view of a modified form of the invention;

Fig. 3 is a vertical section of part of a drainage system comprising drains of the type illustrated in Fig. 1 or Fig. 2, the drains being shown in sections along the line III—III in Fig. 1 or Fig. 2;

Fig. 4 is a horizontal section of part of another embodiment of the invention;

Fig. 5 is a vertical section taken on the line V—V of Fig. 4; and

Fig. 6 is a similar vertical sectional view of a slightly modified embodiment of the invention.

2

While the drain according to the invention may have any suitable cross-section, I have illustrated, by way of example, some drains having a narrow substantially rectangular cross-section each:

The drain according to Fig. 1 is made by fastening two strip or band-shaped layers 1 and 2 of a uniform width together, the surface of the one layer 1 facing the other layer 2 being channelled in the longitudinal direction of the drain. The channels form internal passages 3 in the drain, the two layers bearing on each other at the projections 4.

According to the embodiment shown in Fig. 2, the drain consists of three layers, the outer layers 6 and 7 being of a material pervious to water and capable of preventing fine soil grains from passing therethrough, whereas the intermediate layer has a very great permeability in the longitudinal direction of the drain and is able to withstand the horizontal earth pressure, transmitted by the outer layers, without loosing too much of its permeability. In the example illustrated in Fig. 2, strips or bars 5 are suitably spaced in parallel between two non-channelled layers 6 and 7, and the whole structure is fastened together so as to form longitudinal passages 3.

The fastening may be effected by gluing along the two edges of the drain and, if strips or bars 5 are used, at individual points in the interior of the drain. Instead of gluing, clamping or sewing may be used.

Laboratory investigations have shown that the drains may be made of ordinary unsized cardboard or similar flexible materials. They are made, for instance, of a thickness of one eighth of an inch and of a width of four inches with passages of the cross-section $1/25 \times 1/25$ inches at mutual distances of one fifth of an inch, and the length of each drain may amount to, for instance, 5 to 60 feet.

In Fig. 3, I have shown a section of a drainage system with substantially vertical drains A, B, and C in their positions in a ground 8 the surface of which is indicated at 9. For the sake of clearness, the thickness of the drains is exaggerated in this figure. According to the permeability and compressibility of the soil, and the width and permeability of the drain, and the rate at which the consolidation of the soil is wanted to take place, the spacing d of the drains A, B, C is calculated theoretically. It may vary, for instance, between 3 and 10 feet but should be the same, or nearly the same, in the plane of Fig. 3 as in the direction perpendicular thereto. As will be seen from Fig. 3, the upper ends of the drains are slightly projecting above the surface 9 of the ground, while the lower ends of the drains are terminating in the ground. A layer 10 consisting of sand or gravel is placed upon the surface 9, the

height of said layer being somewhat greater than the height of the projecting portions of the drains. Resting on the layer 10, there is a diagrammatically indicated embankment 11, such as for a highway or a runway for airplanes, exerting a vertical load on the ground 8.

Any suitable means may be used for driving the drains into the ground, an appropriate device for that purpose being described in my above named application Serial No. 762,946.

The material of which the drains consist should be pervious to water, but the pores must be relatively small so as to prevent earth from intruding the drains and obstructing the flow of water. In cases where the earth pressure on the drain is very great, it is necessary, for the purpose of preventing a collapse of the passages, to increase the strength of the drain material in a wet state, which is effected by suitable impregnation. It should then be attended to, however, that the permeability of the drain material is not impaired too much. Further, the drain should be compressible in the longitudinal direction so as to be able to take part in the vertical compression of the ground without being damaged.

From any point of the surrounding earth, the water squeezed out by the load flows approximately perpendicularly to the nearest drain, as indicated by the arrows in Fig. 3, and enters the passages 3. Since there is no outlet at the lower end of the drain, the water travels upwards in the passages 3 and, at the upper end of the drain, enters the sand or gravel layer 10. In this layer, the water flows laterally until being caught by a suitable surface drainage system, if any, not shown in the drawing, or else it flows out from under the embankment.

Laboratory tests have proved that the permeability in the longitudinal direction of a drain according to Fig. 2 is surprisingly great as compared with that of a drain without passages. Thus, thanks to the provision of the passages, the spacing of the drains can be increased, which, of course means economy.

Another embodiment is shown in Figs. 4 and 5 wherein the drain consists of a single strip or band 12 of a flexible material pervious to water and a passage or tube 13 arranged outside the edge of the strip. The passage is formed by a wire helix 14 which is retained in position by means of a securing strap 15 attached to the band, said strap also preventing the earth from penetrating into the helix and in between the helix and the band. The passage 13 is open at its top and terminates near the surface of the ground.

If the band material is of inferior strength in a wet state, it is possible to prevent the same from penetrating into the helix by the edge of the band facing the helix being lined with a filtering strip 16 from fabric or some other suitable material pervious to water, the filtering strip being retained in position by the securing strap 15. The water entering the band 12 from the surrounding earth will flow into the passage 13 substantially in the direction of the arrows shown in Fig. 5 and will then continue to flow upwardly through the passage.

If desired, the wire helix may be made from other material than metal, and it may also be replaced by a perforated tube, consisting, for instance, of network, as shown at 14a in Fig. 6. The securing strap 15 may consist of fabric, cloth, water-proof paper or the like, and it may be secured to the band such as by sewing, past-

ing or stitching. The band may consist of any suitable number of layers. If required, the drain may be provided with a passage at the other edge as well. One or more passages in the interior 5 of the drain are also conceivable, each of such passages being provided with a wire helix or the like, the same being covered by a filter, if desired.

As will be seen from Figs. 1 and 2, the passages 10 3 are arranged relative to the appertaining strip or band so that parts of said strip, as viewed at right angles to their surfaces, are free from passages. As these parts are more rigid against the earth pressure than the parts traversed by passages, the earth pressure will distribute itself unevenly and be greater at the first-named parts than at the latter parts. Thus, to a certain extent the soil itself will bridge over the parts traversed by passages.

The longitudinal passage or passages in the drains may obviously be provided by means other than those shown and described by way of example. The invention is obviously not limited to a plurality of passages in the drains.

25 While in the foregoing description I have confined my consideration to vertical drains, it will be understood that the invention is not confined to exactly vertical drains and passage means, but may equally well be embodied by the use of 30 drains having passage means located at an acute angle with respect to the surface of the ground, for instance, between 90° and 45°.

What I claim is:

1. In a drainage system for accelerating the 35 consolidation of grounds having a very low permeability to water, a plurality of laterally interspaced drains placed in the ground, each of said drains comprising a flexible strip exerted to lateral earth pressure and consisting of a material pervious to water, and said strip having passages 40 extending longitudinally of the drain and opened at the outer end thereof to permit water squeezed out of the surrounding earth through said strip to flow through said passages.

2. In a drainage system for accelerating the 45 consolidation of loaded grounds having a very low permeability to water, a plurality of laterally interspaced drains placed in the ground, each of 50 said drains comprising a flexible strip exerted to lateral earth pressure and consisting of a material pervious to water, and substantially vertically extending passages in said strip, said passages being open at their tops and terminating near the surface of the ground, whereby to permit water squeezed out of the surrounding earth through said strip to flow upwards through said 55 passages onto said surface, said passages being arranged in said strip so that parts of said strip, as viewed at right angles to the surface of the strip, are free from passages.

3. In a drainage system for accelerating the 60 consolidation of loaded grounds having a very low permeability to water, a plurality of laterally interspaced drains placed in the ground, each of 65 said drains comprising a flexible strip exerted to lateral earth pressure and consisting of a material pervious to water, said strip comprising band-shaped layers fastened to each other, the surfaces of said layers facing each other having different geometric shapes so as to provide substantially vertical internal passages therebetween, said passages being open at their tops and terminating near the surface of the ground, 70 whereby to permit water squeezed out of the sur-

rounding earth through said strip to flow upwards through said passages onto said surface.

4. In a drainage system for accelerating the consolidation of loaded grounds having a very low permeability to water, a plurality of laterally interspaced drains placed in the ground, each of said drains comprising a flexible strip exerted to lateral earth pressure and consisting of a material pervious to water, said strip consisting of three layers, the outer layers being of a material pervious to water and capable of preventing fine soil grains from passing therethrough, and the intermediate layer having a great permeability in its longitudinal direction and being adapted to withstand the horizontal earth pressure, transmitted by said outer layers, without loosing too much of its permeability.

5. In a drainage system for accelerating the consolidation of loaded grounds having a very low permeability to water, a plurality of laterally interspaced drains placed in the ground, each of said drains comprising a flexible strip exerted to lateral earth pressure and consisting of a material pervious to water, said strip comprising three interconnected band-shaped layers, the intermediate one of said layers consisting of interspaced bars so as to form substantially vertical internal passages, said passages being open at their tops and terminating near the surface of the ground, whereby to permit water squeezed out of the surrounding earth through said strip to flow upwards through said passages onto said surface.

6. In a drainage system for accelerating the consolidation of loaded grounds having a very low permeability to water, a plurality of laterally interspaced drains placed in the ground, each of said drains comprising a flexible strip exerted to lateral earth pressure and consisting of a material pervious to water, and a flexible perforated tube extending substantially vertically and secured to an edge of said strip, said tube being open at the top and terminating near the surface of the ground, whereby to permit water squeezed out of the surrounding earth through said strip and entering said tube to flow upwards therethrough onto said surface.

7. In a drainage system for accelerating the consolidation of loaded grounds having a very low permeability to water, a plurality of laterally interspaced drains placed in the ground, each of said drains comprising a flexible strip exerted to lateral earth pressure and consisting of a material pervious to water, and a wire helix forming a flexible perforated tube extending sub-

stantially vertically and secured to an edge of said strip, said tube being open at the top and terminating near the surface of the ground, whereby to permit water squeezed out of the surrounding earth through said strip and entering said tube to flow upwards therethrough onto said surface.

8. In a drainage system for accelerating the consolidation of loaded grounds having a very low permeability to water, a plurality of laterally interspaced drains placed in the ground, each of said drains comprising a flexible strip exerted to lateral earth pressure and consisting of a material pervious to water, and a flexible network forming a perforated tube extending substantially vertically and secured to an edge of said strip, said tube being open at the top and terminating near the surface of the ground, whereby to permit water squeezed out of the surrounding earth through said strip and entering said tube to flow upwards therethrough onto said surface.

9. In a drainage system for accelerating the consolidation of loaded grounds having a very low permeability to water, a plurality of laterally interspaced drains placed in the ground, each of said drains comprising a flexible strip exerted to lateral earth pressure and consisting of a material pervious to water, a flexible perforated tube extending substantially vertically and secured to an edge of said strip, said tube being open at the top and terminating near the surface of the ground, whereby to permit water squeezed out of the surrounding earth through said strip and entering said tube to flow upwards therethrough onto said surface, and a layer of a material pervious to water between said strip and said tube.

10. In a drainage system for accelerating the consolidation of loaded grounds having a very low permeability to water, a plurality of laterally interspaced drains placed in the ground, each of said drains comprising a flexible strip exerted to lateral earth pressure and consisting of a material pervious to water, a flexible perforated tube extending substantially vertically and secured to an edge of said strip, said tube being open at the top and terminating near the surface of the ground, whereby to permit water squeezed out of the surrounding earth through said strip and entering said tube to flow upwards therethrough onto said surface, and a longitudinal strap pervious to water, said strap surrounding said tube and being secured to said strip.
